UNITED STATES PATENT OFFICE.

EDGAR BUCHANAN, OF SALINA, KANSAS.

STREET-TRAFFIC SIGNAL.

1,378,320.

Specification of Letters Patent. Patented May 17, 1921.

Application filed October 7, 1920. Serial No. 415,236.

To all whom it may concern:

Be it known that I, EDGAR BUCHANAN, a citizen of the United States, residing at Salina, in the county of Saline and State of Kansas, have invented certain new and useful Improvements in Street-Traffic Signals; and I do declare the following to be a full, clear, and exact description of the invention, such as will enable others skilled in the art to which it appertains to make and use the same.

This invention relates to an improved street traffic signal of the type which is adapted to be embedded in a road-bed at the point of intersection of streets to direct the movement of vehicles.

The principal object of the invention is to provide a signal of the above mentioned type which embodies an illuminating device which directs rays of light to the exterior of the device, thereby permitting the latter to effectively serve at night.

Another and very important object of my invention is to provide a signal device of the above mentioned class which is constructed from substantially indestructible material, and yet is of such construction that provides a very effective means for directing traffic at night.

A further object of the invention is to provide a signal device of the above mentioned class which embodies a chamber in which the illuminating device is disposed, and a bore leading from this chamber through which the rays of light pass, this bore being relatively large and closed by a removable transparent member, and thus providing a handhole, which enables the electric globe to be readily replaced in case it is burnt out.

A still further object of the invention is to provide a signal device of the above mentioned character embodying passages through which the rays of light pass, there being lenses disposed in these passages and these lenses being positioned inwardly of the exterior surface of the device so that they cannot possibly become damaged or broken.

Other objects and advantages of the invention will be apparent during the course of the following description.

In the accompanying drawing forming a part of this specification and in which like numerals are employed to designate like parts throughout the same:

Figure 1 is a side elevation of a traffic signal constructed in accordance with my invention.

Fig. 2 is a top plan view thereof.

Fig. 3 is a central vertical sectional view taken on the plane of the line 3—3 of Fig. 2. Referring to the drawing, wherein the preferred embodiment of my invention is clearly illustrated, it will be seen that the numeral 1 designates a substantially dome-like reinforced concrete body which is provided in its underface with a recess constituting a chamber which is adapted to contain suitable illuminating means to be hereinafter described. Communicating with this chamber and disposed horizontally and extending radially from the center of the body are a plurality of bores 3, and positioned centrally of the body and also communicating with the chamber is a vertical tapered bore 4 which is provided at its outer end with a counter-bore, 5. This body is adapted, as is obvious, to be embedded in a road-bed at the point of intersection of two streets, and it is to be so embedded that the horizontal bores 3 are above the surface of the street. Embedded in the body is a metal structure including a central frusto-conical portion 6 which extends into the tapered bore 4 and a plurality of tubular arms 7 which extend radially from the part 6 into the radial bores 3, terminating adjacent the outer ends of these bores and being provided at these ends with beads 8. In practical use, the inner surfaces of the parts 6 and 7 will be highly polished so that they will assist greatly in reflecting the rays of light out through the bores 4 and 5 to the exterior.

Then they may be readily and easily seen by approaching drivers. At this point, I wish to state that the outer ends of the radial bores beyond the beads 8 are directed upwardly to throw the rays of light in this direction. Secured in the beads 8 are colored lenses 9 which are diagonally inclined with respect to the surface of the road-bed and are arranged inward of the exterior surface of the body to prevent them from becoming injured and broken. Another and relatively larger lens or glass 10 is employed, this lens being removably arranged within a cup-like member 11 which is seated in the aforesaid counter-bore and is centrally apertured and soldered or otherwise secured to the upper end of the truncated cone 6.

Putty 12 or other easily removable material will be employed to retain the lens 10 in position and to permit it to be removed whenever necessary or desired. This tapered bore 5 which the lens 10 covers, permits the rays of light to pass upwardly through it and serves as a hand-hole by means of which the illuminating device may be repaired or removed. For the purpose of permitting heat and gas 10 to escape from the chamber 2, the body is provided with a plurality of vents 13.

The illuminating device may be of any suitable or desired construction. For the purpose of illustration, I have shown an ordinary electric bulb 14 and a socket carrying and supporting member 15 provided with binding posts for connection of the necessary electric wires 16. This device is positioned on a block 17 and the latter is arranged on bricks or the like 18. With this arrangement, it will be seen that the bulb will be caused to extend upwardly into the conical part 6 of said metal structure and will be positioned in alinement with the radial passages of the body to effectively distribute its rays through these passages to the exterior.

With the construction and arrangement I employ, during rainy weather, water would 30 naturally deposit in the pockets formed at the ends of the radial bores. To prevent such depositing of the water and to permit it to flow onto the pavement or street, I provide drain notches or recesses 19 which communicate with the outer ends of the bores in the manner clearly shown.

From the foregoing description, it will be seen that I have devised an extremely advantageous and effective traffic signaling 40 device which is practically indestructible, because of the fact that it is cast of concrete or other similar material. In case the electric bulb should become broken or burnt out, it can be easily replaced due to the fact that the device includes a hand-hole to permit me to do this very easily and readily. The lenses arranged at the outer ends of the bores are positioned inward of the exterior surface of the body and consequently 45 they cannot become very easily broken or damaged. The metal structure which is embedded in the body is extremely advantageous because it provides a very simple and effective means for supporting the lenses 50 and, in view of the fact that its interior surfaces are highly polished, it serves as a plurality of reflectors for effectively distributing the rays of light. In addition to these features, I have provided novel means 55 for draining water from the pockets formed at the outer ends of the radial bores and direct the rays of light upwardly at an angle so that they can be readily and easily seen at a distance but at the same time will not 60 interfere with the driver's vision. These

and other advantages and features of my invention have, no doubt, become apparent from the foregoing description.

A careful consideration of the description taken in connection with the accompanying drawing, is thought to be sufficient to enable persons skilled in the art to which this invention relates, to obtain a clear understanding of the same, therefore, a more lengthy description is deemed unnecessary.

Since probably the best results may be obtained with the construction and arrangement shown, this construction and arrangement is taken as the preferred embodiment of my invention. However, I wish it to be understood that various minor changes in the shape, size, and arrangement of parts may be resorted to without departing from the spirit of the invention or the scope of the subjoined claims.

I claim:

1. A street signal of the type set forth comprising a practically indestructible body including a chamber for containing illuminating means, and a plurality of horizontal radiating bores communicating with the chamber and adapted to distribute the rays of light, said bores being offset upwardly at their outer ends and lenses disposed in the offset portions of the bores.

2. The structure set forth in claim 1, there being notches formed at the outer ends of the bores communicating with the offset portions thereof and with the exterior of the body, these notches serving as drain-grooves.

3. A street signal comprising a dome-like substantially indestructible one-piece body to be embedded in a road-bed, the same being provided in its underface with a recess forming a chamber, and being further provided above said recess with a plurality of relatively long cylindrical horizontal radial bores and a relatively large vertical tapered bore, the latter having a counterbore at its outer end, lenses closing the outer ends of all of said bores, being disposed inward of the exterior surface of the body to prevent them from becoming broken by vehicle wheels which accidentally pass over the body, and an illuminating device in the aforesaid chamber, being removable through the aforesaid vertical tapered bore.

4. A street signal comprising a body of substantially indestructible material to be embedded in a roadbed, being provided in its underface with a recess forming a chamber, and being also provided with a plurality of horizontal radial bores and a vertical tapered bore, a reflecting structure arranged in the body, including a central conical part fitted into the tapered bore, and a plurality of radial tubular arms extending through the radial bores, lenses connected to said arms and conical part, being arranged inward of the exterior surface of the body,

and an illuminating device in the chamber, including a bulb extending into the tapered bore and positioned in alinement with the horizontal bores.

- 5 5. A street signal comprising a body composed of a substantially indestructible material, said body being provided in its under-face with a recess forming a chamber, and being also provided with a plurality of horizontal radial bores communicating with the
- chamber and further provided with a vertical tapered bore also communicating with the chamber, an illuminating device in said chamber, separate and independent reflectors for each of said bores, and a lens for 15 closing the outer ends of each bore.

In testimony whereof I have hereunto set my hand.

EDGAR BUCHANAN.
